UNITED STATES PATENT OFFICE

WYMAN EATON AND ELLSWORTH J. WESTCOTT, OF CHICAGO, ILLINOIS, ASSIGNEES TO
FREYN ENGINEERING COMPANY, OF CHICAGO, ILLINOIS, A CORPORATION OF MAINE

HOT BLAST STOVE

Application filed September 9, 1929. Serial No. 391,188.

Our invention relates to hot blast stoves, and has particular reference to a hot blast stove which may be built from an old stove or from one already in service, which has a chimney at the top of the shell, of which there are a great many types. The stove may be built new if desired, although it is designed primarily of a form into which stoves already in service may be converted without 50 tearing down the entire shell and structure of the present stoves.

An object of the present invention is the provision of a hot blast stove having a large heating surface in the regenerating chambers, which is necessary in the modern type of stove in order to conserve the heat units and also to heat the blast properly when the stove is on blast.

A great many hot blast stoves are now in 20 use which have been in service for a considerable period of time. Many improvements have been made in recent years in the checkerwork used in regenerative chambers of these stoves, and, as is well known, checkerwork requires attention frequently in order 25 to allow the products of combustion to flow freely through the checkerwork, and, what is equally or more important, to allow the blast to flow freely through the checkerwork in order 30 to become thoroughly heated when the stove is on blast. These stoves vary in type, but nearly all of them include an outer shell, a lining inside of the shell in contact with the shell, and a circular brick structure inside 35 of the lining and spaced apart therefrom with a passage formed between the said lining and the wall forming the brick structure. An arched top is provided which is supported by the brick structure, and is spaced from 40 the top of the shell, leaving a chamber through which the cold blast and the products of combustion must pass. The cold blast passes downward between the wall of the brick structure and the lining for the shell 45 and enters the regenerator chambers at their

bottoms. Sometimes the combustion chamber is located in the center of the stove, but at other times in the side. With this type of stove it is extremely difficult to keep the arch over the center properly positioned, because 50 the arch cannot be anchored securely against the outside shell without restricting the outside passage to such an extent that the flow of gases therethrough is restricted. In our improved form the arch can be anchored by the 55 outer shell so that it remains securely in position, and in rebuilding the stoves it is only necessary to tear out the lining and build an outside flue or conduit, so that the steel work, including the shell, chimney, conduits and 60 the like, are all utilized in the new structure, and in effect a new stove is provided at a minimum expense.

These and other objects of our invention will be better and more fully understood by 65 reference to the accompanying drawings, in which—

Figure 1 is a vertical sectional view of a hot blast stove embodying our invention; and

Figure 2 is a cross sectional view on the 70 lines 2—2 of Figure 1.

Referring now specifically to the drawings, in which like reference characters refer to like parts throughout, a shell 10 is provided, usually cylindrical in shape, mounted upon suitable foundations which have nothing to do with our present invention. The shell 10 has a chimney 11 secured thereto at the top and opening out to the atmosphere, through 75 which the products of combustion and waste gases pass. A chimney valve 12 is provided, which is operated by a lever 13, by means of a chain 14 which extends to the ground, so that the valve 12 can be opened or closed by 80 the operator during the operation of the stove. A cold blast conduit 15 is provided which is connected to a cold blast main 16 leading to the blowing engines or any suitable source of air supply under pressure, a 85

valve 17 being provided for the control of the flow of the cold blast into the stove.

A lining 18 is provided, made of brick or the like, which is built up against the inside 5 of the shell 10 throughout its entire length, and has an arch portion 19 at the top portion thereof, this arch being solid and extending across the entire top of the lining 18. A partition wall 20 is built, preferably arcuate 10 in shape, having its ends in engagement with the wall 18, so that a combustion chamber 21 is provided at one side of the hot blast stove and a regenerative chamber 22 is provided at the opposite side of the combustion 15 chamber 21. The regenerative chamber 22 is filled with brick checkerwork, which is built up from the bottom of the regenerative chamber on suitable supports common to stoves of this type. This checkerwork may vary 20 and be made of different sizes of bricks, it being understood that passages are formed between these bricks through which the gases pass in one direction and the blast passes in the opposite direction, absorbing the heat 25 from the checkerwork as the blast passes through the stove. A pipe 23 is provided at one side of the shell 10, communicating with the combustion chamber 21, this pipe 23 providing inlet means for the gas which 30 is consumed in the combustion chamber 21, and also as an outlet for the hot blast as the blast passes from the stove when the stove is on blast. Suitable valves (not shown) control the flow of the gas inward 35 and the hot blast outward into suitable conveying pipes to the blast furnace.

At the opposite side of the shell an outlet conduit 24 is provided having an end 25 placed thereon, with a sleeve 26 mounted 40 therein to which an end cap 27 is secured to provide means for cleaning the outlet pipe 24, and also to obtain access to the lower side of the checkerwork if desired. A pipe 28 is provided, which is connected to the pipe 24 45 at its lower end and passes upward alongside the shell 10 and on the outside thereof, and terminates at the chimney 11, this pipe being connected at a point opposite the cold blast pipe 15, so that when a stove is placed 50 on blast, the blast passes directly across the chimney 11 and into the pipe 28. Checker-work 29 may be placed throughout the length of the pipe 28 if desired, or a small portion of its length at the bottom of the shell, and 55 thus provide in addition the regenerative chamber in the pipe 28, if desired. The use of this checkerwork will depend a great deal upon the operating conditions at each particular plant.

60 In operation of the device, the gas enters through the pipe 23 and is burned in the combustion chamber 21, the heated gases and products of combustion passing downward through the regenerative chamber 22 out of 65 the pipe 24 and up the pipe 28 to the chimney

11. The operator, when a stove is on gas, opens the chimney valve 12 and closes the blast valve 17, so that the products of combustion from which most of the heat units have been absorbed by the checkerwork, pass 70 outward through the chimney valve 12. When it is desired to put the stove on blast, the gas is shut off from the pipe 23, the chimney valve 12 closed, and valve 17 opened, so that cold blast admitted through the pipe 15 75 passes downward through the pipe 28, through the checkers 29 and upward through the regenerative chamber 22, and thence downward through the combustion chamber 21 and out through the pipe 23, where it 80 passes into the hot blast main by suitable piping and valves in common use in connection with plants of this type.

It will thus be understood that by changing 85 the partition walls and the addition of the outside pipe 28 with a suitable connection therefore, a good many hot blast stoves which are now in use can be remodeled and continued to be used in service in the same manner as if the stoves were completely torn 90 down and replaced with stoves of the usual type having an outlet leading to a separate chimney directly at the bottom of the checker-work.

Though a preferred embodiment of the 95 present invention has been described in detail, many modifications will occur to those skilled in the art. It is intended to cover all such modifications that fall within the scope of the appended claims. 100

We claim:

1. A hot blast stove comprising, in combination, a stove shell, a vertically extending wall in said shell, said wall stopping short of the top of the shell whereby combustion and heating chambers are formed, a lining for said stove having a closed top portion extending over the heating and combustion chambers and extending over and spaced from the top of the wall between said chambers, a chimney supported by said stove shell, a valve in said chimney, a cold air intake into said chimney below the said valve, a conduit into said shell at one side thereof whereby air and gas is supplied to said stove, and a second conduit extending from the heat exchange side of the stove at the lower portion thereof adjacent the outside of the stove shell and leading into said chimney at a point below the valve. 110

2. A hot blast stove comprising a metallic shell, a refractory lining therefor having a closed dome-shaped top, a vertically extending partition wall terminating short of the dome-shaped top whereby combustion and heat interchange chambers are formed, a chimney supported by the said shell, a valve in said chimney, a cold air intake pipe connected to said chimney below said valve and above the stove shell, a pipe leading into the 120 125 130

bottom of the combustion chamber forming an intake for gas and air for combustion purposes and an outlet for hot blast, and a pipe outside of the shell connected to said chimney below said valve and connected to the stove at the bottom of the heat interchange chamber and forming a conduit for the outlet of the products of combustion and an inlet for the cold blast.

10 Signed at Chicago, Illinois, this 4th day of Sept. 1929.
